TUNABLE MAGNETRON

Marshall C. Pease, Boston, Mass., and Frank A. Record, Potsdam, N. Y., assignors to the United States of America as represented by the Secretary of War

Application January 29, 1946, Serial No. 644,164

6 Claims. (Cl. 315—40)

1. Anode structure for a magnetron, comprising

This invention relates to electrical apparatus, and more particularly to improvements in tunable magnetron radio frequency oscillators.

Various methods of tuning magnetron radio frequency oscillators have been devised in the past. Many of these methods were designed to change the frequency by coupling some externally tuned reactance into the magnetron resonant cavity. These designs were accompanied by a certain amount of unavoidable power loss in the tuning reactance and in the intermediate coupling between the reactance and the magnetron cavity.

An object of the present invention is to provide a magnetron with a mechanical adjustment for the resonant frequency of the magnetron cavity resonators.

A further object of the invention is to accomplish tuning of a magnetron with negligible power losses.

Other objects and advantages of the invention will be apparent during the course of the following description.

In the accompanying drawing forming a part of this specification and in which like numerals are employed to designate like parts throughout the same,

Fig. 1 is a top view of a tunable plural cavity magnetron embodying the principles of the principles of the present invention, with the top cover removed showing the anode structure and a portion of the body structure broken away to illustrate the plunger rod. The bellows is shown partially cross-sectioned; the plunger rod is not cross-sectioned.

Fig. 2 is a side view of the anode structure itself.

Fig. 3 is a top view of one of the fixed metallic laminations composing the anode structure of Fig. 2.

Fig. 4 is a top view of one of the moveable metallic laminations composing the anode structure of Fig. 2.

Referring to Fig. 1 wherein is shown a preferred embodiment of this invention, the numeral 10 designates a substantially rectangular parallelepiped structure with one semi-cylindrical end which serves as the housing for the plural cavity magnetron 11. Concentrically disposed about central cathode 12 is the substantially cylindrical anode structure 13. Anode structure 13 contains a plurality of individual oscillator cavities 14 leading by radial off-center slots 15 into the cathode-anode space 16 which is concentrically disposed about cathode 12.

Fig. 2 shows a side view of the anode structure 13 removed from magnetron 11. Anode structure 13 is composed of a plurality of metallic washer-like laminations 20, 21, and 22 assembled one above the other to form the completed anode structure 13.

Alternate metallic laminations 20 composing anode structure 13 are fixed laminations and the other laminations 21 and 22 are moveable laminations.

The fixed metallic lamination 20, as is shown in Fig. 3, has circular 14' corresponding to cavities 14 of Fig. 1 and radial slots 15' corresponding to the radial slots 15 of Fig. 1. Two bosses 23, 23 are provided on the circumference of lamination 20 to maintain it in a fixed position within housing 10.

The moveable metallic washer-like lamination 21, as is shown in Fig. 4, has circular slots 14'' corresponding to the cavities 14 of Fig. 1 and radial slots 15'' corresponding to the radial slots 15 of Fig. 1. A fixed-pivot hole 29 is provided on a boss 30 which projects from the circumference of moveable lamination 21. A second boss 31 projecting from the circumference of laminations 21 has a tie hole 32 and a pivot slot 33.

Moveable laminations 22 (Fig. 2) are identical with moveable laminations 21, as shown in Fig. 4, save that the boss 31 extends only slightly beyond tie hole 32 as shown by the dotted line in Fig. 4.

Referring again to Fig. 1, a fixed-pivot pin 40 passes through the fixed-pivot hole 29 of the moveable laminations 21 and 22. A tie bolt 41 passes through the tie holes 32 of the moveable laminations 21 and 22 to maintain their alignment. A moveable plunger rod 42 passes between the uppermost and lowermost moveable laminations 21. A pivot pin 43 is affixed to rod 42, said pivot pin 43 being guided in the pivot slots 33 of moveable laminations 21. Moveable plunger rod 42 has a slot 44 which is guided by the fixed pin 45. Fixed pin 45 is affixed to the housing 10, and serves as a stop for moveable plunger rod 42.

Vacuum seal 50 consists of bellows 51 soldered at one end to the enlarged end of plunger rod 42 and at the other end to the bushing 52 which projects from the housing 10.

The operation of the device as shown in Fig. 1 is as follows:

Movement of plunger rod 42 is transmitted through the moving pivot 43 and the slot 33 to the moveable laminations 21. Movement of

plunger rod 42 causes the moveable laminations 21 to rotate relative to the fixed laminations 20 in a horizontal plane about fixed-pivot pin 40. The rotation of the moveable laminations 21 with respect to the fixed laminations 20 will alter the dimensions of the cavities 14 and of the radial slots 15 thus causing a change in the resonant frequency of each cavity 14 and hence of the frequency of the magnetron 11.

A tuning range of the order of 10% is readily attainable by the use of this device. The manifold variation, which alters the dimensions of each cavity 14 and of each slot 15, is noteworthy as causing a large change of frequency for a small rotation of the moveable laminations 21 with respect to the fixed laminations 20. The power output is not appreciably affected.

While there has been described what is at present considered to be the preferred embodiment of this invention, it will be obvious that various changes and modifications may be made therein without departing from the scope of the invention.

What is claimed is:

1. A tuneable magnetron oscillator including a substantially cylindrical anode structure, an evacuated housing surrounding said anode structure, said anode structure having a central cylindrical space surrounded by a plurality of cylindrical cavities concentrically arranged about said space and opening into said space through radial slots, said anode structure comprising a stack of metallic washer-like laminations, alternate laminations in said stack being moveable with respect to the others, a plunger rod connected with said moveable laminations, vacuum seal means flexibly connecting said plunger rod to said housing, and external tuning drive means connected to said plunger rod, whereby said plunger rod may be moved thereby moving said moveable laminations with respect to said fixed laminations and varying the dimensions of said cylindrical cavities and said radial slots and consequently varying the frequency of said magnetron oscillator.

2. A tuneable magnetron including a substantially cylindrical anode structure, said anode structure having a central cylindrical space surrounded by a plurality of cylindrical cavities concentrically arranged about said space and opening into said space through radial slots, said anode structure comprising a stack of metallic washer-like laminations, alternate laminations in said stack being moveable with respect to the others and means connected to said moveable laminations for moving said moveable laminations with respect to said other laminations.

3. In a tuneable magnetron, an anode structure having a plurality of cavity resonators, said anode structure comprising a stack of metallic

laminations, alternate laminations in said stack being moveable with respect to the others and means connected to said moveable laminations for moving them into said cavity resonators to thereby vary the resonant frequency of said cavity resonators.

4. In a tuneable magnetron, an anode structure having a plurality of cavity resonators, said anode structure comprising a stack of metallic laminations, a number of the laminations in said stack being moveable with respect to the others and means connected to said moveable laminations for moving them into said cavity resonators to thereby vary the resonant frequency of said cavity resonators.

5. A tuneable magnetron including a substantially cylindrical anode structure having a central cylindrical space surrounded by a plurality of cylindrical cavities concentrically arranged about said space and opening into said space through radial slots, said anode structure comprising a stack of metallic washer-like laminations, alternate laminations in said stack being moveable with respect to the others, and means connected to said moveable laminations for rotating said moveable laminations with respect to the other laminations to thereby constrict each of said cylindrical cavities and said radial slots.

6. A tunable magnetron oscillator having an anode structure, said anode structure comprising substantially identically shaped washer-like laminations, each of said laminations being circular in cross-section and having a central circular space surrounded by a plurality of circular holes concentrically arranged about said space and opening into said space through radial slots, all of said laminations being arranged in a stack with said spaces, said holes and said slots in substantial coincidence, alternate laminations in said stack being rotatably movable with respect to the others, and means connected to said moveable laminations for rotating said moveable laminations with respect to said other laminations.
